UNITED STATES PATENT OFFICE.

GEORGE W. DALLIMORE, OF OAKLAND, CALIFORNIA.

RAILWAY TIE.

1,427,522.

Specification of Letters Patent. Patented Aug. 29, 1922.

Application filed February 14, 1922. Serial No. 536,425.

To all whom it may concern:

Be it known that I, GEORGE W. DALLIMORE, a citizen of the United States, residing at Oakland, in the county of Alameda and State of California, have invented new and useful Improvements in Railway Ties, of which the following is a specification.

While I have illustrated in the drawing and described in the specification a railway tie of the cross-tie type, it will be understood that the invention may be embodied as a switch tie, a bridge tie, or in other standard and suitable devices of this character for use in supporting the rails of railroads. The primary object of the invention is the provision of a railway tie that is unusually durable, strong, and well adapted for forming part of the roadbed of the railway, and in which the load of passing trains may properly be distributed and shocks and vibrations due to passage of rolling stock be absorbed to reduce to a minimum the possibility of cracking or breaking the tie. With these and other purposes in view the invention consists essentially in a reinforced concrete tie and rail bearings, as will be hereinafter more specifically pointed out and claimed.

In the accompanying drawings I have illustrated one complete example of the physical embodiment of my invention, as a cross tie for railways, in which the parts are combined and arranged according to the best mode I have thus far devised for the practical application of the principles of my invention, and it will be understood that changes and alterations may be made therein within the scope of my claims without departing from the spirit of my invention.

Figure 1 is a longitudinal sectional view at one end of a tie, showing the rail supported thereby in section, with parts of the tie in elevation.

Figure 2 is a transverse, vertical sectional view of the tie, at line 2—2 of Figure 1.

Figure 3 is an end elevation of the rail bearing or saddle, one of which is used beneath each rail of the track.

Figure 4 is a top plan view showing the rail clamped to the rail bearing, and showing in dotted lines a cushion for the rail, forming part of the tie.

Figure 5 is a top plan view of the rail bearing.

Figure 6 is an enlarged, detail sectional view, at line 6—6 of Figure 4 showing the

means for attaching the rail flanges to the rail bearing.

In order to illustrate the relation of parts I have illustrated a standard rail having the head 1, web 2 and base or flanges 3, forming part of a railway track, and it will of course be understood that the two ends of the cross tie 4 are of similar construction. The body of the tie 4 is of concrete, cement, or fashioned of other plastic material and has embedded therein a longitudinally extending core 5 which is preferably of metal in the form of a spiral or helical coil for reinforcing the tie. The helical core is located centrally of the body of the tie, extending throughout its length and terminating at suitable points with relation to the ends of the tie. The cement or concrete fills the interior of this spirally tubular core and also fills the spaces between its coils, for reinforcement, except at points directly beneath the track rails, where wooden cores 6 are illustrated. These cores perform the functions of cushions for absorbing shocks and vibrations from passing trains, and while I have shown and described them as of wood, it is apparent that other suitable material may be used when desired. That cores, which are of cylindrical shape to fit within the helical or tubular core, may be tapered at one end to facilitate their entrance into the metallic core, and as shown in Figure 1 are located directly beneath the rails equidistant from the ends of the tie, and form part of the rail bearing.

A pair of saddles or rail bearings 7 in the form of metal castings are used with each tie, and the saddles as shown are each fashioned with lateral wings 8, 8, and a central arch 9, the latter conforming to the exterior of the helical core. The rail bearing or saddle is disposed transversely of the tubular core with the arch 9 nested over the top of the core and the two wings 8, 8, straddling the core, and attached thereto by means of rivets or other fastenings indicated at 10. At one side of the saddle three of these fastening devices or rivets are secured to respective coils, while at the other side of the saddle two coils are secured to the saddle, but it will be understood that the number of fastening devices may be varied provided the saddle is firmly and rigidly attached to the core as shown. Preferably the body of the saddle is flush with the top of the con-

crete tie, and above the surface of the tie is a bearing plate 11 for the rail, which is integral with the saddle or rail bearing, of sufficient length to insure a support for the rail, 5 and of sufficient width to adapt the saddle or rail bearing to various sizes of rail flanges 3. In the drawings a maximum size of rail flange 3 is shown supported on the rail plate 11, which is of greater width than the rail 10 flange 3, and of course narrower rail flanges may be supported on the rail plate shown.

At opposite sides of the rail plate are formed sockets 12 and 13, extending inwardly toward the center of the rail plate 15 and preferably of dovetail shape in cross section. These sockets extend transversely of the rail plate and saddle and are spaced apart the required distance, and as shown best in Figure 6 each socket is prolonged 20 into an opening 14 extending through the remaining width of the rail plate and through the plate at the side opposite the socket. The horizontal sockets and holes are designed to receive the rail clamps which 25 are of special construction as best shown in Figure 6. The clamps embody a longitudinally threaded head 15, of dovetail shape in cross section conforming to the shape of the socket, and an integral upper clamp lug 16, 30 adapted to fit over the outer edge of the rail flange 3. The shank 17 of the bolt has a head 18, and the bolt is passed through the bolt hole 14, with its threaded end engaged in the clamp head or nut 15. A 35 spring grip washer 19 is interposed between the bolt head 18 and the rail plate to provide a friction lock against movement of the bolt.

In assembling the parts and forming the tie, the two saddles 7 are first located the proper distance apart to correspond with the gauge of the railway track, and the helical core is then fastened within the saddles. The two wood cores or cushions are then entered from opposite ends of the helical core 40 and forced into place. These assembled parts are placed, face down, or in reverse position of that shown in Figure 1, upon the bottom plate of a concrete form, and the concrete, cement, or other plastic material is poured into the form or mold, filling into 45 and around the helical core and saddles to complete the body of the tie. The quantity of material or concrete utilized may be determined for various purposes, and the 50 length, thickness, and width of the tie are made according to standards required in the maintenance of way for the railroads.

The jaws or lugs 16 of the clamp heads 55 15 conform to the incline of the top surface of the rail flanges, thus adapting them to slight variations in thickness of the flanges. And the length of the sockets 12 and of the heads 15 therein is such as to permit the 60 head to be drawn, by turning the bolt, with-

in the socket for fastening a rail of less width than that shown for instance in Figure 6. Thus the threaded end of the bolt is of sufficient length to draw the clamp-head into its socket 12.

The dovetail shape of the head 15 and its socket 12 provide a firm anchorage for the head in the rail-plate, and the jaw or lug 16 of the clamp head firmly retains the flange in place on the rail plate. The clamp head 75 is thus readily adapted to fasten the rails to the rail bearings or saddles, and is adjustable with facility to the rail flange at either the outer side or inner side of the rail. The rails are held against spreading, and the opposing clamp heads and bolts firmly hold the rails against strains, or from turning over, in both straight track construction, as well as on curves in the track.

The wood cores or cushions displace the 80 concrete within the helical, tubular core, to form a cushion, and as they are embedded in the tie are protected from deterioration. They are in direct contact with the tubular core, beneath the rail bearing and form a 85 cushion sufficient to absorb shocks and vibrations and prevent strain on the concrete body of the tie.

The formation of the rail bearings or 90 saddles in connection with the tubular core and cushion cores, insures the distribution of weight of a passing train over a comparatively wide area of the metal reinforcement or core, as the saddles are directly attached to a plurality of coils at each side of 95 the tubular core, and the load is concentrated at this cushioned point beneath the saddle.

From the above description taken in connection with my drawing it will be apparent 105 that I have provided a tie of such character as will fulfill the requirements and perform the functions essential to a comparatively perfect device of this type.

Having thus fully described my invention, 110 what I claim as new and desire to secure by Letters Patent is:—

1. The combination in a railway tie of a helical metallic core therein and spaced rail bearings fitting over said core, cushion members within said core below said rail bearings, and means for fastening rails to said rail bearings.

2. The combination in a concrete railway tie and a tubular core therein, of spaced rail 120 bearings secured to said core, cushion members within said core beneath said bearings, and means for fastening rails to said rail bearings.

3. The combination in a concrete railway 125 tie, of a helical reinforcing core therein, saddles forming rail bearings having wings secured to said helical core, bearing plates on said saddles, and means for fastening rails to said bearing plates.

4. The combination in a concrete railway tie, of a helical reinforcing core, a saddle supported transversely of said core and having wings secured to a plurality of coils of said helical core, a cushion member within said core beneath the saddle, and means for fastening a rail to said saddle.
5. The combination in a railway tie with a tubular core, of a saddle, wings on said saddle fastened to the core, a rail plate on the saddle having opposed sockets and bolt holes, clamp-heads in said sockets, threaded

bolts in said holes engaging said heads, and jaws on said heads for engaging the rail flanges.

15

6. The combination with a railway tie including a saddle having a rail plate and spaced, oppositely extending transverse sockets and bolt holes, of threaded clamp heads in said sockets having a dovetail shape in cross section, bolts in said holes engaging said heads, and rail engaging jaws on said heads.
